UNITED STATES PATENT OFFICE.

LUTHER L. KNOX, OF NILES, OHIO, ASSIGNOR TO KNOX PRESSED & WELDED STEEL COMPANY, OF PITTSBURGH, PENNSYLVANIA, A CORPORATION OF PENNSYLVANIA.

FURNACE-DOOR.

1,103,297.

Specification of Letters Patent. Patented July 14, 1914.

Application filed August 19, 1912. Serial No. 715,726.

To all whom it may concern:

Be it known that I, LUTHER L. KNOX, a resident of Niles, in the county of Trumbull and State of Ohio, have invented a new and useful Improvement in Furnace-Doors, of which the following is a full, clear, and exact description, reference being had to the accompanying drawings, forming part of this specification, in which—

10 Figure 1 is a front view of one form of furnace door embodying my invention; Fig. 2 is a similar view of a portion of a door showing a modification; Fig. 3 is a section on the line III—III of Fig. 1; Fig. 4 is a section on the line IV—IV of Fig. 2; and Fig. 5 is an end view partly broken away of the saddle member of Figs. 1 and 2.

15 My invention has relation to furnace doors, and more particularly to water-cooled furnace doors which are provided with poke openings therethrough. These water-cooled doors are usually made of welded metal sheets and being comparatively thin, are worn by the operation of the poker working 20 through the poke opening. They are also apt to be injured by the contact of the poker therewith in introducing it into the doors.

25 My invention provides means of simple and effective character for protecting those portions of the walls of the poke openings which are most liable to injury.

Referring first to the construction shown in Figs. 1 and 3, the numeral 2 designates a hollow water-cooled sheet metal furnace 30 door body. 3 is a water supply pipe extending downwardly into the door from the connection 3^a and terminating in a transverse spray arm 4, at the lower inwardly offset portion of the door. 5 designates the 35 offtake connection for the heated water. The numeral 6 designates a poke opening formed through the door body. This opening is preferably formed with the double beveled wall 7. 8 designates a protecting 40 saddle which may be of cast iron or other suitable material and which is adapted to be inserted and seated in the lower portion of the poke opening, as shown in Figs. 1 and 3. The saddle member is preferably V-shaped or depressed on its upper surface, as indicated at 8^a and is provided with the flange 9. It is also shown as having in its bottom a notch 10, to receive a projecting lug 11 on the lower wall of the opening. 12 45 designates a pivoted butterfly closure which

can be moved in position to close or inclose the poke opening. The opening 6 is narrower at the bottom than at the top, and the saddle 8 is of corresponding wedge shape. In order to seat said saddle, it is 50 turned on edge and inserted into the upper portion of the opening 6. It is then turned within the opening and dropped down into proper position. The engagement of the lug 11 with the notch 10 holds the saddle to 55 its place. When the saddle member becomes worn or injured, it can readily be removed or replaced by a new one. Its use greatly extends the life of the furnace door, since it receives all the wear of the poker. 70

In Figs. 2 and 4, I have shown the application of my invention to another form of door which is provided with the inset projection 13, around the poke opening 6^a, the latter being of rectangular form. In this 75 case, the saddle member 14 is adapted to fit within the lower portion of the rectangular opening and is formed with the inwardly projecting retaining portion 15, which engages the beveled wall 16 of the inset portion of the poke opening. 80

In the construction shown in Figs. 1 and 3 I prefer to first assemble the various parts, and then form the opening 6, by pressing the sheets toward each other to form the double beveled walls 7. I then cut out the metal between the walls, and weld the sheets to each other at the junction of the bevels. 85

I do not limit myself to the use of protecting members of the particular form 90 which I have herein shown and described, as it will be obvious that they may be made of various forms, according to the size and shape of the poke opening and of the character of the doors to which they are applied. 95

I claim:—

1. A furnace door having a poke opening therethrough and a protecting member removably seated in said opening, said member comprising a metal body which extends 100 across and fills the lower portion of said opening, the side portions of said body also extending upwardly above its central portion and along the side walls of said opening, substantially as described. 105

2. A hollow water-cooled furnace door having a poke opening therethrough, and a protecting member removably seated in the lower portion of said opening, said member forming a rest for a poker or the like, and 110

- also having side portions which extend upwardly above said recess and protect the lower portion of the side walls of said opening, substantially as described.
5. 3. The combination with a furnace door having a poke opening therethrough, of a removable member seated in the lower portion of said opening, said member having a flange at its outer end which abuts the outer 10 surface of the door adjacent to the opening, substantially as described.
4. A sheet metal water-cooled furnace door having a poke opening therethrough, said opening having its walls formed with 15 a double bevel, and a protecting member seated on the lower wall of said opening and having a V-shaped groove therein to fit the double bevel of said wall; substantially as described.
- 20 5. The combination with a furnace door

having a poke opening therethrough, said opening being of less transverse width at its lower portion than at its upper portion, of a protecting member of wedge shape seated in the lower portion of said opening 25 and forming a rest for a poker or the like, said member and the lower portion of the opening having interfitting portions which prevent endwise movement of the member in the opening, and said member being insertible into and removable from the upper portion of said opening when turned into an endwise position, substantially as described.

In testimony whereof, I have hereunto set 35 my hand.

LUTHER L. KNOX.
